UNITED STATES PATENT OFFICE

FREDERICK G. CARLSON, OF BROOKLYN, NEW YORK

SPACING MEANS FOR MOLD FORMS

Application filed March 28, 1928. Serial No. 265,282.

This invention relates to spacing means for mold forms, and more particularly to devices of that character which are used for the purpose of spacing apart the opposite 5 side walls of a concrete mold form. Heretofore, wood spacer beams have been arranged between the spaced walls of the mold form to be removed as the pouring of the concrete between the form walls progresses.

10 Considerable difficulty attends the removal of these spacers particularly where the form is built up to a considerable height so that many of the spacer bars are not removed and become incorporated in the concrete 15 structure after it has set or hardened. Disintegration of these wood spacer bars results in the leakage of water through the wall structure.

In order to overcome this difficulty, it 20 has been proposed to provide spacing means for the mold form walls consisting of rods extending between the walls and threaded at their opposite ends for connection with cone-shaped members bearing at their larger ends 25 against the inner faces of the mold walls. Additional threaded rods are then connected to the other ends of these cone-shaped members and extend outwardly through the mold walls and through suitable supporting beams 30 therefor and to the ends of the latter rods and against said beams clamping devices are applied. After the concrete has set, the mold walls are removed, by releasing the clamping devices and disconnecting the latter rods from the cone members, after which 35 said cone members are rotated and disconnected from the spacing rod which is incorporated in the concrete structure. The cavities in the faces of the wall resulting 40 from the removal of the cone members are then filled in with concrete. While this device is more or less efficient, it is comparatively expensive, due to the necessity of providing the cast metal cone members with 45 internal threads and also threading the ends

of the several rods constituting each of the spacing devices. Also the assemblage of the several parts consumes considerable time and is somewhat difficult.

It is the primary object and purpose of 50 my present invention to provide a mold form spacing means of the above kind which however, may be very easily and quickly assembled and wherein the use of threaded connections between the individual parts is 55 entirely avoided.

It is also another object of the invention to provide the three primary spacing elements arranged between the mold forms, 60 each of which is constructed of relatively light sheet metal and is of hollow or tubular form so that the tie rod which receives the form clamps may be readily inserted through or removed from these assembled elements.

With the above and other objects in view, 65 the invention consists in the improved spacing means for concrete mold forms and in the form, construction and relative arrangement of its several parts as will be herein- 70 after more fully described, illustrated in the accompanying drawings, and subsequently incorporated in the subjoined claims.

In the drawing, wherein I have illustrated 75 one simple and practical embodiment of the invention, and in which similar reference characters designate corresponding parts throughout the several views,

Figure 1 is a fragmentary vertical section 80 of a mold form illustrating one practical embodiment of the present improvements;

Fig. 2 is a sectional view through a portion 85 of the molded concrete wall after the mold form has been removed, and

Fig. 3 is a perspective view partly in section showing the essential parts of the device disassembled.

Referring in detail to the drawing, 5 designates the opposite side walls of a mold form made up of planks or boards secured 90

together by the vertically extending beams 6.

Between the spaced side walls 5 of the mold form at suitable vertically and horizontally spaced intervals, spacing means is arranged to retain the walls 5 in predetermined fixed spaced relation to each other. As herein shown, each of these spacing devices includes a pair of cone-shaped members 7 formed from sheet metal of the requisite thickness and provided at its larger end with an annular cylindrical flange 8. The smaller end of said cone member is formed with an annular shoulder 9 and the reduced longitudinal extension 10.

In conjunction with these two cone members, a single straight section of sheet metal tubing 11 of the required length is employed, said tubing being of such internal diameter that it may be readily fitted over the reduced extensions 10 of the members 7 to bear at its ends against the shoulders 9.

In applying the spacing means, the cone members 7 are arranged with their end flanges 8 bearing against the inner faces of the mold walls 5 around openings which have been formed through said walls and the spacing tube 11 is then engaged at its opposite ends over the reduced necks or extensions 10 of said cone members.

Horizontal beams 12 are secured across the vertical beams 6, said beams 6 and 12 having openings to register with each other and with the openings in the mold wall 5. The tie rod 13 is then inserted through said registering openings and through the two cone members 7 and the spacing tube 11 as clearly seen in Fig. 1 of the drawings. Suitable form clamps 14 are then engaged upon the opposite ends of the rod 13 and against the beams 12 to hold the mold walls in tight abutting contact against the ends of the cone members 7 against the outward expanding pressure of the concrete when poured between the walls of the mold.

The concrete is then poured into the mold and settles around the cone members 7 and the spacing tubes 11 of the several spacing devices. It will however, be observed that the concrete does not come into contact with the tie rod 13 which is entirely covered by the parts 7 and 11 of the spacing means. After the concrete has set or hardened, the form clamps 14 are then removed and the tie rods 13 can be easily withdrawn through the spacing tubes 11 and the members 7. By means of a suitable tool inserted through the cone members 7 and engaged with the end of the reduced neck 10, the cone member can be pulled outwardly and easily disconnected from the end of the spacer tube 11 which remains in the wall structure as shown in Fig. 2 of the drawings. The cavities in the faces of the wall resulting from the removal of these cone members can then

be filled in with concrete, and the interior of the spacing tube 11 can also be filled with concrete if desired. These sheet metal spacing tubes 11 can be produced at a fraction of the cost of the solid spacer rods having threads on their opposite ends heretofore used in this art so that the loss of these tubes which remain in the wall structure will be a negligible expense. Also by the elimination of the threaded connections between the parts, the assemblage of the cone-shaped members with the spacer elements and the subsequent removal of said members can be much more easily and quickly effected and without liability of breaking up the concrete surrounding the cone-shaped members which is incident to a rotative movement of these members.

From the foregoing description considered in connection with the accompanying drawings, it will be seen that I have devised a very simple and efficient spacing means for the walls of concrete molds whereby time, labor and expense incident to the erection of mold forms may be very appreciably reduced. At the same time, a very substantial and durable structure is provided which when properly assembled between the mold walls, will rigidly support and retain said walls in the desired spaced relation to each other. I have herein shown and described a particular form and construction of the several parts of the spacing means, which I have found to be very desirable in practical use. However, the cone-shaped members 7 with which the spacer tube is connected might be of other detail structure than that herein shown, and other alternative means might also be employed for retaining these members 7 in assembled relation with the opposite ends of the spacing tube. It is therefore, to be understood that in practice, I reserve the privilege of resorting to all such legitimate changes in the detail form and construction of the several elements as may be fairly embodied within the spirit and scope of the invention as claimed.

I claim:

1. A spacing device for walls comprising a pair of hollow sheet metal cones having flanges at their wider ends engaging against the inner sides of the wall and having shoulders and extensions at their smaller ends, a sheet metal tube having its ends fitted over the extensions of the two cones and abutting at its ends against the shoulders of the two cones, a tie rod passing through the walls, cones and tube, and clamp means on the tie rod.

2. A spacing device for walls, comprising a pair of cones having flanges at their wider ends adapted to engage against the inner sides of the wall and provided on their smaller end with shoulders and extensions,

a tube arranged between the cones and adapted for interfitting engagement at its ends over said extensions of the cones and adapted to abut at its opposite ends against said shoulders of the two cones, an unthreaded tie rod passing through the walls, cones and tubes, and clamp means carried upon the opposite end portions of the tie rod.

10 In testimony that I claim the foregoing as my invention, I have signed my name hereto.

FREDERICK G. CARLSON.
